UNITED STATES PATENT OFFICE.

JACOB THOMAS, OF NEWARK, DELAWARE.

WALL-PAPER-TRIMMING MACHINE.

1,098,770.

Specification of Letters Patent.

Patented June 2, 1914.

Application filed November 1, 1913. Serial No. 798,684.

To all whom it may concern:

Be it known that I, JACOB THOMAS, a citizen of the United States, residing at Newark, county of Newcastle, and State of Delaware, have invented certain new and useful Improvements in Wall-Paper-Trimming Machines, of which the following is a specification.

My invention relates to the manufacture of wall paper and particularly to a machine adapted for trimming the irregular edges of fancy borders.

It has been the usual practice to trim the irregular edges of border patterns by hand. Such hand trimming consumed a large portion of the time of the paper hanger thereby increasing the cost of papering a room when such designs as required irregular trimming were employed. It is therefore advisable to furnish such borders to the trade with the edges trimmed, and it is the primary object of my invention to provide a machine particularly adapted for such work. Efforts have been made to provide means for mechanically trimming borders, but so far as I am aware, such devices have consisted of attachments to the wall paper printing machines, and as such have been found undesirable for obvious reasons, among others, that the freshly printed paper is not sufficiently dry when passing to the trimming device to prevent injury from the latter.

The object of my invention is to provide a trimming machine which shall be separate and distinct from the printing machine and by means of which the paper may be trimmed at any time that it is desired to furnish the same in trimmed condition to the trade; whereby the untrimmed paper may be kept in stock by the manufacturer and trimmed in the desired quantities as necessary for the market.

A further object of my invention is to provide a paper trimming machine of the character mentioned upon which the printed paper may be placed in large rolls, trimmed, and rewound into the size rolls required for the trade.

A further and particular object of my invention is to provide in a machine of the class mentioned, means for initially registering the cutting device with the design on the paper.

A still further and particular object of my invention is to provide means in a de-

vice of the class mentioned whereby the relative speeds of the paper and of the cutting device may be varied at the will of the operator to maintain proper registry between the cutting device and the design or for bringing the same into register while the machine is running, should they become out of register.

Other objects will appear hereinafter.

With these objects in view my invention consists generally in a paper trimming machine comprising a rotary platen and a rotary knife roller co-operating therewith, means for supporting a roll of printed paper, means for feeding the paper from said roll to said platen and knife roller, rewinding mechanism and means for feeding the trimmed paper from the platen to said mechanism.

My invention further consists in a trimming machine as mentioned equipped with means under the control of the operator for starting and stopping the rewinding mechanism as desired.

My invention further and more particularly consists in a trimming machine as mentioned further characterized by means for normally driving the platen and the knife roller at uniform peripheral speed and means for varying the relative peripheral speeds of the same.

My invention further consists in a wall paper trimming machine comprising the platen and knife roller as above mentioned in combination with means for shifting the knife roller toward or from the platen, means for shifting the same transversely of the platen and means for shifting the same peripherally of the platen.

My invention further consists in a paper trimming machine comprising the platen and knife rollers together with the shifting means above mentioned in combination with means for driving said platen and knife rollers, and means for initially rotating the knife roller to bring the knife pattern initially into proper registry with the design longitudinally of the paper.

My invention further consists in a wall paper trimming machine embodying the features above stated and further equipped with improved tension devices for maintaining a proper tension on the web of paper at its various positions in the machine.

My invention further consists in various

details of construction and arrangements of parts all as will be fully described hereinafter and particularly pointed out in the claims.

5 My invention will be more readily understood by reference to the accompanying drawings forming a part of this specification and in which—

- Figure 1 is a front elevation of a wall paper border trimming machine embodying my invention in its preferred form, Fig. 2 is a side elevation of the forward portion of the same, Fig. 3 is a side elevation partially in section of the rear portion of the machine, Fig. 4 is a front elevation upon an enlarged scale of the driving and speed changing mechanism for the knife roller, Fig. 5 is a longitudinal section of the same, Fig. 6 is a plan view of the same, Fig. 7 is 10 a vertical section taken on substantially the line $x-x$ of Figs. 4 and 5 and illustrating the bearing and driving gear for the platen, Fig. 8 is a side elevation of the knife roller supporting device and adjacent portion of 15 the frame, Fig. 9 is a transverse section of the same on the line $y-y$ of Fig. 8, Fig. 10 is a longitudinal section of the same on the line $z-z$ of Fig. 8, Fig. 11 is an elevation of the same upon the opposite side from that 20 shown in Fig. 8 and with a portion of the supporting device removed, Fig. 12 is an elevation, partially in section of the mechanism for initially rotating the knife roller to bring the design of the knife into register with the pattern of the paper, Fig. 13 is 25 an end elevation of the same, and Fig. 14 is a detail view illustrating the means for returning the speed changing clutch operating lever to initial position.
- 40 Referring now to the drawings 1 indicates the frame at the forward end of the device comprising two similar upright portions 1^a and 1^b connecting at their lower ends by transverse members 2 and at the upper end 45 by a transverse arch bar 3. Extending rearwardly from the arch bar 3 are a pair of longitudinally disposed frame members 4 supported at their rear ends by uprights 5. The uprights 5 are provided with brackets 6 to 50 support the arbor 7 of a roll 8 of the printed paper which is to be trimmed. Arranged upon a shaft 9 above the roll 8 is a drum 10 for feeding the web A of paper from the roll.
- 55 11 indicates a small roller mounted above the drum 10 and co-operating with the same. Mounted upon the shaft 9 is a driven pulley 12 which is coupled to said shaft 9 by an ordinary clutch, not shown, 13 indicating 60 the lever for operating the clutch. By this arrangement the feeding of the paper from the roll 8 may be regulated as desired. As the web of paper passes from the drum 10 it is received upon the floor or other support

as at a from whence it passes through suitable tension devices to the trimming mechanism, *per se*, which will be hereinafter fully described.

Extending transversely through the frame 1 is a driven shaft 14, and arranged above the shaft 14 is a parallelly disposed shaft 15 upon which is mounted the platen 16. The platen 16 comprises a large cylindrical drum having its outer face 17 covered or prepared with suitable material for co-operation with the knife or knives of the knife roller. The shaft 15 is mounted in suitable bearing blocks 18 and is provided adjacent one side of the machine with a large gear 19 meshing with a pinion 20 on the driven or power shaft 14. By this arrangement, when the machine is in operation, the drum 16 is driven at a constant speed.

The bearing blocks 18 are mounted in suitable guides or ways 21 arranged on the frame of the device, and suitable means are provided for raising and lowering the blocks to raise and lower the platen. To this end an oscillatory shaft 22 is mounted transversely of the frame in brackets 23 extending upwardly from the frame members 1^a and 1^b . A pair of short arms 24 are fixed to the shaft 22 and are connected by links 25 with the blocks 18, whereby rotary movement of the shaft 22 will raise or lower said blocks.

26 indicates an operating lever fixed to one end of the shaft 22, and 27 indicates a quadrant adjacent said lever and provided with a stop 28 under which the lever 26 is adapted to be engaged for maintaining the platen in raised position when desired. The quadrant 27 is connected at one end to the frame member 1^a as shown and a brace 29 is provided for steadyng the opposite end thereof.

30 indicates the knife roller provided with a shaft 31 mounted in adjustable bearings 32. Provision is made for moving the knife roller toward and from the platen in a path substantially radially thereto, for adjusting the same vertically with relation to its path of travel toward and from the platen, and for adjusting the same transversely across the face of the platen. To this end the frame members 1^a and 1^b are provided with forwardly and downwardly projecting extensions 33 which are substantially U-shaped forming parallel arms 34 and 35 equipped with ways 36 and 37 respectively, and connected by a transverse lower portion 38. Slidably mounted in the ways 36 and 37 is a slide comprising parallel guide portions 39 connected by a pair of parallel portions 40 adjacent their lower outer ends. The members 39 are substantially co-extensive in width with the adjacent portion of the frame and are provided

upon the inner edges with flanges 41 engaging the adjacent edges of the frame or ways as shown clearly in Figs. 9 and 11. The connecting portions 40 are preferably co-extensive in width with that of the members 39 and flanges 41 so that the inner faces of the flanges and portions 40 form a plane surface as shown clearly in Fig. 11.

42 indicates a pair of aligned notches or ways formed in the opposite flanges 41. Bearing against the flanges 41 and coplanar faces of the portions 40 is a plate 43 provided with a vertically disposed rib 44 engaging in the ways 42 whereby said plate 15 may move vertically with relation to the slide. The plate 43 is provided with a transversely extending arm 45 terminating in an enlarged portion 46 having its outer face in the plane with the outer edges of 20 the ways 36 and 37 and adjacent frame portions. Secured to the portion 46, as by tap screws 47 is a plate 48, preferably coextensive in length and breadth with the plate 43 and serving to hold said plate and arm 25 45 in position.

The bearing blocks 32 are secured to the arms 45 upon opposite sides of the machine and the bearing block upon the right hand side is transversely adjustable thereon. 30 To this end said block is provided with a dovetailed portion 49 fitting in correspondingly formed ways in the respective arm 45 and a screw 50 is threaded into the dovetailed portion and swiveled into the member 35 formed by the plates 33 and 38. By turning the screw 50 it is obvious that the respective block 32 will be adjusted laterally. The shaft 31 is provided with annular ribs or collars 51 engaging upon opposite sides 40 of the adjustable bearing block 32 whereby when said block is adjusted the knife roller will be shifted transversely of the platen. Threaded through the portion 38 of the frame extension is a screw 52 provided with a hand wheel 53 for turning the same. The opposite end of the screw 52 is reduced in diameter as at 54 and provided with an enlarged head 55 arranged 55 between the transverse portions 44 of the slide, forming a swiveled connection. It is obvious that by turning the screw 52 the slide together with the knife roller will be moved toward or from the platen and the arrangement is preferably such that the screw 52 is substantially radially disposed with relation to the platen when in operative position so that the movement of the knife roller toward and from the platen will be in a substantially radial path. One 60 of the portions 40 of the slide is provided with a lateral extension 55' and the plate 48 is formed with a housing 56 to receive the same. Swiveled through the housing 56 is a screw 57 which is threaded through

the extension 55. By turning the screw 57 65 the plates 43 and 48 together with the arm 45 and block 32 are raised or lowered. By the three separate adjustments above described the knife roller may be brought into proper relation with the platen to produce a perfectly clean sharp cut and by means of the screw 50 the knife roller may be shifted to bring the knife into proper lateral registry with the design of the paper. The means for bringing the knife 75 into proper registry with the design longitudinally of the web of paper will be described fully hereinafter.

The drive shaft 14 is extended a considerable distance beyond the frame 1 and upon this extended portion of the shaft is arranged the driving mechanism for the knife roller and the means for varying the speed of the same. 58 indicates a bracket extending from one side of the frame 1 and 85 provided with a suitable brace 59.

Fixed to the shaft 14 as by a set screw 60 is a substantially cylindrical member 61 provided with a worm gear 62 preferably formed integrally therewith. Loosely 90 mounted on the shaft adjacent the member 61 is a member 63 having an annular flange 64 thereon and a gear 65 keyed thereto. The gear 65 meshes with an idler 66 which in turn meshes with the gear 67 on the knife shaft 31. Fixed to the flange 64 is a bracket 68 provided with bearings 69 for a short shaft 70. The shaft 70 is provided with a worm 71 arranged between the bearings 69 and with a worm wheel 72 which in turn 100 meshes with a worm 73 on a shaft 74 projecting perpendicularly from the flange 64 or parallel with the shaft 14. It is obvious that the motion of the member 61 is transmitted through the gearing 62, 71, 72, 73 105 and shaft 74 to the member 63 and the gear 65, the gear 65 thereby normally rotating at the same speed as the shaft 14; and the gears 19 and 20, 67 and 65 are so proportioned as to normally give the same 110 peripheral speeds to the platen 16 and knife roller 30. The idler 66 is mounted upon a slotted arm 75 which is adjustably mounted on a bracket 76 on the frame 1 in order that said idler may be brought into proper relation with the gears 65 and 67 after the shaft 31 has been adjusted.

Loosely mounted on the shaft 14 adjacent the member 61 is a clutch member 77 provided with a fixed gear 78 meshing with a gear 79 on the end of shaft 74. It is obvious that normally the clutch member 77 travels with the members 61 and 63 and at the same speed therewith. A second clutch member, 80, is loosely mounted on the shaft 14, and is provided with a fixed gear 81 which meshes with a gear 82 on a jack shaft 83, said jack shaft being provided with a

second gear 84 meshing with a gear 85 keyed as at 86 to the shaft 14. The gears 81, 82, 84 and 85 are proportioned to drive the clutch member 80 at a greater angular velocity than the shaft 14.

87 indicates a lever for shifting the clutch member 80, the same being provided with a yoke 88 engaging a peripheral groove 89 in said member. The lever 87 extends forwardly and rests upon a horizontal bar 90 projecting from the side of the frame and is provided with an upwardly extending ear 91. Fixed to the bar 90 is a pair of U-shaped members 92, one upon each side of the lever 87, and slidably mounted on each of said members is a rod 93, the inner ends of which impinge against the ear 91. The spring 94 is interposed between a stop 95 on each of said rods and the outer portion 20 of the respective member 92 for projecting the rods inwardly against the ear 91, and heads 96 are formed on the outer ends of the rods to limit the inward movement thereof. By this construction the lever may 25 be moved either to the right or left for the purpose hereinafter described, and when released will be immediately returned to normal position.

Should the operator notice that the paper 30 has lagged or that the knife is in advance of the pattern on the paper he at once moves the lever on the left to throw the clutch member 80 into engagement with the clutch member 77 causing the latter to travel at the same speed therewith or at a greater speed than its normal speed when traveling with the members 61 and 63. This causes the gear 78 to travel faster than the member 61 thereby turning the shaft 74 through 35 the medium of the gear 79, and, through the train of worm gearing, slows down the speed of the member 63 and gear 65, thereby slowing down the speed of the knife. As soon as the knife is in proper register with 40 the pattern the lever 87 is released and returns to normal position disengaging the clutch members, and the platen and knife continue to travel at a uniform peripheral speed.

50 Should it be necessary to increase the speed of the knife the lever 87 is moved to the right. Fixed to the lever is a depending arm 97 provided with a friction face 98 which engages a peripheral flange 99 on the 55 clutch member 77. This stops the rotary movement of the member 77 and gears 78 causing the gear 79 to revolve about the gear 78 with a planetary movement, causing the gear 79 to rotate in an opposite direction 60 from that in which it rotates when the clutch members 77 and 80 are in engagement, thereby increasing the rotary speed of the knife roller. From this position the lever is returned to normal position by the mechanism above described on the arm 90.

The knife roller 30 is equipped with knives 30' which conform to the outline of the platen to be trimmed and it is therefore necessary, before starting the machine into operation to insure proper registry of the 70 knife with the pattern. The adjustment of the knife roller transversely of the web has been described hereinbefore, and I will now describe the means for initially registering the knife with the design longitudinally of 75 the web.

Fixed to the end of the knife roller shaft 31 is a collar 100 provided in its periphery with a worm gear 101. Loosely mounted upon the shaft 31, adjacent said collar, is a member 102 to which the gear 67 is secured as by a key 103. The member 102 is provided with an arm 104 upon which is mounted a bracket 105 carrying a worm 106 which meshes with the worm gear 101, thus locking 85 the gear 67 against relative rotation on the shaft except when said worm is operated. The shaft 107 of the worm is provided with a head 108 equipped with apertures 109 to receive a pin or other instrument for turning the same. 110 indicates a weighted arm on the member 102 to balance the arm 104, and the parts carried thereby. The gear 67 being in mesh with the gear 66 is held firmly against movement except when the 90 machine is in operation, therefore, after the web of paper is in position on the drum, the knives may be brought into proper registry therewith, longitudinally of the web, by turning the worm 106 which turns the 95 shaft and the knife roller carried thereby.

Suitable means must be provided for feeding the web of paper through the machine to the rewinding mechanism, to be described hereinafter, and for maintaining a proper 105 tension on the same. I have hereinbefore described how the web is fed from the roll to the point *a*. From here the web passes upwardly and through a suitable guide and tension device. Located upon the frame 110 members 4 are a plurality of transversely extending bars 111, preferably formed of wood and in practice I find three to be sufficient. Adjustably supported on the bars 111 is a pair of longitudinally disposed guide 115 members 112 which are arranged with their inner faces spaced apart a distance equal to the width of the paper web. The paper passes upwardly over the first bar 111, under the middle bar and over the last bar as 120 indicated in Fig. 2. Depending from the forward ends of the members 4 are angularly disposed brackets 113 upon which are secured bearing members 114. Mounted between the members 114 are a plurality of 125 rollers 115. Hingedly connected to the members 114 is a frame 116 provided with a plurality of rollers 117 which are positioned intermediate the rollers 115.

The web *A* of paper passes between the 130

two sets of rollers, 115, 117 as shown clearly in Fig. 2, and the tension on the web may be readily adjusted by means of the screw 118 and hand wheel 119, the former being attached at one end to the bearing frame 114 and the opposite end extending through an aperture in the free end of the frame 116. From the last roller 115 the web passes over a roller 120 adjacent the platen drum and thence to said platen. After being trimmed the paper passes upwardly over a roller 121 at the top of the machine and thence between power driven rollers 122 and 123. From the last mentioned rollers the web passes on to an endless belt 124 arranged on suitable rollers mounted in brackets 125 and 126 on the frame members 4. 127 indicates a tension device for maintaining a proper tension on the belt.

Located at the rear end of the frame members 4 and directly beneath the rear end of the belt 124 is an inclined member or chute 128 leading to a box 129, the bottom of said box being formed of the upper lap of an endless belt 130. Located to the rear of and adjacent the box 129 is the rewinding mechanism. The paper from the belt 124 passes down the incline 128 on to the belt 130 forming the bottom of the box 129 and the last mentioned belt is slowly driven so as to move the paper deposited in the box toward the rewinding mechanism as indicated by the arrow in Fig. 2.

131 indicates the rewinding table above which is supported in suitable brackets the rewinding spindle 132 upon which is mounted a pulley 133.

134 indicates a power driven pulley connected by a loose belt 135 with the pulley 133.

40 Pivottally mounted upon the stand of the table 131 is a lever 136 having a weighted arm 137 for maintaining the same in raised position. The lever 136 is also provided with a depending arm 138 carrying a roller 139 which engages the belt 135. By depressing the lever 136 by means of the pedal 140 the roller 139 is forced against the belt 135 which tightens the same causing the spindle 132 to be driven. The web is fed to 50 the spindle 132 over a roller 141 and an incline 142 and a pivotally mounted knife 143 is provided adjacent the spindle at the rear end of the incline 142 to sever the web when sufficient paper has been wound on the 55 spindle.

I claim:

1. In a wall paper trimming machine, a platen and a coöperating knife roller in combination with means for supporting a 60 roll of printed paper, rewinding mechanism, a conveyer for delivering the trimmed paper to a point adjacent said rewinding mechanism and manually operable means adjacent said rewinding mechanism for severing the 65 web of paper, substantially as described.

2. In a wall paper trimming machine, a platen and a rotary knife roller coöperating therewith, rewinding mechanism, a supporting member adjacent said rewinding mechanism, means for delivering the trimmed 70 paper to said supporting member and a manually operable knife extending transversely across said member, substantially as described.

3. In a wall paper trimming machine, a 75 power shaft and two driven shafts in combination with gearing connecting one of said driven shafts with said power shaft, a fixed member and a loose member mounted on said power shafts, means connecting said 80 fixed member and said loose member, means for operating the last said means for varying the angular relation between said fixed member and said loose member and gearing connecting said loose member and the second 85 driven shaft, substantially as described.

4. In a wall paper trimming machine, a platen roller and a knife roller, means for normally driving said rollers at a uniform peripheral speed and means for varying the 90 speed of one of said rollers, substantially as described.

5. In a wall paper trimming machine, a platen roller and a knife roller, in combination with a power shaft, gearing connecting 95 said power shaft and said rollers for driving the latter at a normal uniform peripheral speed and means interposed in the gearing to one of said rollers for varying the speed of the same, substantially as described. 100

6. In a device of the class described, a power shaft and two driven shafts in combination with gearing connecting said power shaft and one of said driven shafts, a fixed 105 member on said power shaft, a loosely mounted member on said power shaft, gearing connecting said loosely mounted member and the second driven shaft, means connecting said fixed member and said loosely mounted member, a pair of clutch members 110 loosely mounted on said power shaft, one of said clutch members being geared to said connecting means, means for driving the other clutch member at a different angular velocity from that of the power shaft and 115 means for throwing said clutch members into and out of engagement.

7. In a device of the class described, a power shaft and a pair of driven shafts in combination with gearing connecting one of 120 said driven shafts and said power shaft, a member fixed to said power shaft and provided with a worm gear, a second member loosely mounted on said power shaft, a worm carried by said loosely mounted member and meshing with said worm gear, a pair of clutch members loosely mounted on said power shaft, gearing connecting one of said clutch members and said worm, gearing connecting the other clutch member and said 125 130

power shaft for driving said clutch member at a different angular velocity from said shaft and means for throwing said clutch members into and out of engagement.

5. 8. In a wall paper trimming machine, a platen shaft and a knife roller shaft, in combination with a drive shaft, gearing connecting said drive shaft and said platen shaft, a fixed member on said knife roller shaft, a

10 gear wheel rotatably mounted on said last mentioned shaft, an adjustable connection between said fixed member and said gear wheel whereby said shaft may be initially rotated to set the knife, and gearing connecting said gear wheel and said drive-shaft,

15 substantially as described.

9. In a device of the class described, a power shaft and a pair of driven shafts in combination with gearing connecting one of

20 said driven shafts and said power shaft, a member fixed to said power shaft and provided with a worm gear, a second member loosely mounted on said power shaft, a worm carried by said loosely mounted

25 member and meshing with said worm gear, a pair of clutch members loosely mounted on said power shaft, gearing connecting one of said clutch members and said worm, gearing connecting the other clutch

member and said power shaft for driving 30 said clutch member at a different angular velocity from said shaft, the first said clutch member being provided with an annular flange, a lever adapted when moved in one direction to throw said clutch members into 35 engagement, and a brake arm on said lever adapted to engage said flange when said lever is moved in the opposite direction, substantially as described.

10. In a wall paper trimming machine, a 40 rotary platen and a knife roller coöperating therewith, means for adjusting said knife roller radially with relation to said platen, means for adjusting the same transversely of said platen, means for normally driving 45 said platen and said roller at a uniform peripheral speed, means for varying the speed of said roller, and means for initially rotating said knife roller, substantially as and for the purpose specified.

50 In testimony whereof I have signed my name to this specification in the presence of two subscribing witnesses.

JACOB THOMAS.
